C. B. JENKINS

TROLLEY SWITCH

3. Filed July 25, 1923

3. FIG. 1.

FIG. 2.

FIG. 3.

FIG. 4.

C. B. JENKINS INVENTOR
BY *Victor J. Evans*
ATTORNEY

UNITED STATES PATENT OFFICE.

CHARLES B. JENKINS, OF MORGANTOWN, WEST VIRGINIA.

TROLLEY SWITCH.

Application filed July 25, 1923. Serial No. 653,767.

To all whom it may concern:

Be it known that I, CHARLES B. JENKINS, a citizen of the United States, residing at Morgantown, in the county of Monongalia and State of West Virginia, have invented new and useful Improvements in Trolley Switches, of which the following is a specification.

This invention relates to switches, and more particularly to what I term a trolley switch.

One of the main objects of the invention is to provide a switch of simple construction and operation specially adapted for use in coal mines for automatically cutting off the current to a trolley wire leading into the side passages or to the heading in the mine, so as to prevent leakage of current. A further object is to provide a switch of the character stated which may be readily produced and installed at small cost and which can be quickly and easily operated by hand when required. Further objects will appear from the detail description.

25 In the drawings:—

Fig. 1 is a side view of the switch;

Fig. 2 is a top plan view;

Fig. 3 is a section taken substantially on line 3—3 of Fig. 1;

30 Fig. 4 is a section taken substantially on line 4—4 of Fig. 1.

The switch includes a block or base 1 of seasoned and varnished wood or other suitable electrical insulating material. Bolts 2 are secured in the upper face of this block or base providing means for securing the base to the mine roof, though it will be understood that any other suitable or preferred means for supporting the base may be provided. At each end of the under face of base 1 I provide a socket member 3 which is adapted to receive the end portion of a trolley wire 4 secured in the member 3 by means of a set screw 5 or in any other suitable or preferred manner. Two resilient jaws 6 extend from each of the socket members 3, and the lower edges of these jaws are preferably rounded or beveled downwardly and outwardly at 6^a. A switch blade 7 is rockably mounted at its central portion, at 8, in a bracket 9 secured to the under face of base 1 midway between socket members 3. Blade 7 is formed of two arms 7^a and 7^b which are disposed at an upwardly directed obtuse angle to each other, and this

blade is positioned to operate in the plane of the socket members, the end portion of arm 7^a fitting snugly between the jaws 6 of the adjacent socket member 3 when blade 7 is rocked into one operative position so as to raise arm 7^a, this arm being withdrawn from between the jaws 6 when the blade is rocked in the other direction as in Fig. 1. As will be noted more clearly from Fig. 1, the arms 7^a and 7^b are so relatively disposed that, when either arm is raised, it is in horizontal position and is in alignment with the socket with which this arm cooperates. Arm 7^b is provided, at its outer end, with an upwardly projecting arcuate contact member 10 which connects arm 7^b to an upper arm 11 extending from the central portion of blade 7, arms 7^b and 11 forming with contact member 10 a substantially triangular frame the base portion or member 10 of which operates between and is at all times in contact with jaws 6 of the adjacent socket member 3. The block 1 is provided with a cut-out or groove extending from its under face to accommodate this frame so as to permit rocking of blade 7 about pivot 8 for raising or lowering either of the arms 7^a or 7^b, selectively.

To permit the blade 7 to be readily operated by hand I provide an operating rod 12 which is rockably mounted transversely of the upper face of block 1 and is held against displacement by strap members 13. This rod is bent into substantially U-shape and is provided, at the outer end of each arm, with a gripping member or handle 14 of electrical insulating material. At its central portion rod 12 is bent to provide an elongated U-shaped element 15 which extends through a slot provided in the outer end of a link 16 which extends through a slot 17 through block 1, this link being pivoted at its lower end, at 18, in a recess 19 provided for this purpose in arm 7^a of blade 7. With handles 14 in substantially horizontal position link 16 is depressed, arm 7^a of blade 7 being out of contact with jaws 6 of the adjacent socket member 3 and arm 7^b being raised into horizontal position.

In practice the switch is installed in the mine so that the trolley wire 4 leading from the main passage is connected to the socket member 3 at the right hand end of the switch as considered in Figs. 1 and 2, the trolley wire 4 which is connected to the socket mem-

ber at the left hand end of the switch leading to a siding or passage in the mine which leads to the heading. The trolley wheel of a mine locomotive traveling in the main pas-

8 sage of the mine and desiring to enter a side passage will travel upon wire 4 toward the switch from the righthand end thereof and will pass from socket member 3 onto arm 7^b of blade 7, after which the trolley wheel 10 will contact with arm 7^a raising the latter arm into horizontal position. This automatically connects socket member 3 at the left hand end of the switch to trolley wire 4 of the main passage so as to supply current 15 to the trolley wire leading to the heading. On return of the locomotive arm 7^b will be raised into its original position and arm 7^a will be depressed thus automatically shutting off the current to the trolley wire 20 leading to the heading. This effectually prevents any loss or leakage of current in the sidings or in passages leading to the heading.

By providing rod 12 and associated parts 25 the switch blade 7 may be readily and safely operated by hand for connecting or disconnecting a trolley wire leading to a heading to or from the trolley wire in the main passage. This is of particular importance in mines in 30 which machines are used for cutting the coal. Coal cutting machines commonly in use are not provided with trolley poles and wheels it being the practice, when it is desired to move the machine, to supply current 35 to the motor by means of a contact member which is mounted on a stick or rod of electrical insulating material and is held by the operator in contact with the trolley wire. As the machine travels at comparatively slow 40 speed, when the switch is reached blade 7 can be rocked so as to raise arm 7^a into operative position by means of handles 14 and rod 12 thus permitting the machine to obtain current after it has traveled through 45 a siding or passage to the heading. When the machine returns blade 7 may be rocked into its original position by means of handles 14 and associated parts so as to cut off 50 the current from the trolley leading to the heading. I thus provide a switch of very 55 simple and highly efficient construction which is automatically operated by the mine locomotives for supplying current to and cutting current off from trolley wires leading 60 into sidings or passages and to the heading, this switch being also provided with means whereby it can be safely and easily operated 65 by hand, the means for operating the switch by hand in no way interfering with its automatic operation by the trolley wheels of the 70 mine locomotives. By having the arms 7^a and 7^b of blade 7 disposed in angular relation and so arranged that when either arm is raised it is in horizontal position, I eliminate 75 all unnecessary jars caused by the

trolley wheel passing from the socket member 3 onto the adjacent raised arm of blade 7.

What I claim is:—

1. In a switch of the character described, 70 a base of electrical insulating material, socket members mounted on the base and provided with contact elements, a blade rockably mounted intermediate its ends on the base and disposed to be moved into and out of 75 contact with the contact elements of one of the socket members in accordance with rocking of said blade, the blade being provided with a member disposed to be in contact with the contact elements of the other socket 80 member at all times, and manually operated means mounted on said base for rocking the blade in either direction.

2. In a switch of the character described, 85 a base of electrical insulating material, socket members mounted on the base at each end thereof and each provided at its inner end with contact elements, a blade rockably mounted intermediate its ends between the socket members and disposed to be moved 90 into and out of contact with the contact elements of one of the socket members in accordance with rocking of the blade, said blade being provided with a contact member 95 at all times in contact with the contact elements of the other socket member, and means mounted on the base for manually operating the blade.

3. In a switch of the character described, 100 a base of electrical insulating material, socket members mounted on the under face of the base at each end thereof, each of said socket members being provided at its inner end with a contact element, a blade rockably mounted intermediate its ends on the under 105 face of the block and operating in the plane of said socket members, the blade including two connected arms disposed at an upwardly directed obtuse angle such that either arm when raised is in alignment with its co-operating socket member, one of the arms of the blade being provided with an upwardly projecting contact member disposed to at all 110 times contact with the contact element of the adjacent socket member.

4. In a switch of the character described, 115 a base of electrical insulating material, contact elements mounted on the under face of the base at each end thereof, a switch blade rockably mounted intermediate its ends on the under face of the base and having one arm disposed to engage with the adjacent contact element when said arm is raised and to be moved out of contact with said adjacent contact element when the arm is depressed, the other arm of said blade being provided with a contact member disposed to at all times be in contact with the other contact element, means for connecting said contact elements to electrical conductors, an op- 120 125 130

erating rod rockably mounted on the base, and connections between said rod and the switch blade for rocking the blade about its pivot in accordance with rocking of said rod.

5. In a switch of the character described, a base of electrical insulating material, contact elements mounted on said base at each end thereof and adapted to be connected to 10 electrical conductors, a switch blade rockably mounted intermediate its ends on the base between said contact elements, one arm of the blade being disposed to be moved into and out of contact with the adjacent contact 15 elements in accordance with rocking of the blade and the other arm of said blade being

provided with a contact member disposed to at all times contact with the other contact elements, an operating rod rockably mounted on the base, a link passing through the 20 base and pivoted at its lower end to one arm of said blade, said rod being provided with a central angularly disposed element and with terminal angularly disposed elements, said central element being loosely inserted through 25 the upper end of the link, and handles of electrical insulating material secured on the terminal angularly disposed elements of the rod.

In testimony whereof I affix my signature.

CHARLES B. JENKINS.
